UNITED STATES PATENT OFFICE.

HENRY E. HUBBARD, OF CHICAGO, ILLINOIS, ASSIGNOR, BY MESNE ASSIGNMENTS, TO ADDRESSOGRAPH COMPANY, OF CHICAGO, ILLINOIS, A CORPORATION OF DELAWARE.

PRINTING DEVICE.

Application filed May 5, 1927. Serial No. 183,884.

This invention relates to improvements in printing devices of that class which comprise a plurality of printing forms and an information card carried by a frame and adapted to be stored in accordance with a card index system or stacked in a pile, and run through an addressing or other printing machine for taking an impression from the form. These devices are used not only for printing addresses, but they are now made to print a great deal of additional information, parts of which are liable to change with more or less frequency. The invention comprises improvements upon the printing device of Patent No. 1,375,683 patented April 26, 1921.

The object of the invention is to provide a printing device comprising a frame having retaining means stamped from the frame and suitably disposed thereon to receive a plurality of printing plate sections, the sections being arranged one above the other in edge contact but capable of being independently inserted in and removed from the frame.

The invention also has for its object to construct and dispose the retaining means in a novel manner so that the printing plate sections may be made of relatively large size without increasing the size of the frame.

In the accompanying drawings I have illustrated my invention in a preferred embodiment in which:

Fig. 1 is a front elevation of the printing device.

Fig. 2 is a rear elevation.

Fig. 3 is an edge view partly in section on the line 3-3 of Fig. 1, and

Fig. 4 is a section on the line 4-4 of Fig. 1.

Referring to the drawings the frame 5 is provided at its top with a bead 6 and at its bottom with a bead 7 on the front thereof and at its ends with spacing flanges 8 on the back thereof. There are three separate and independent printing plate sections removably mounted on the frame and each bearing type characters embossed thereon. All of these sections are engaged with and disengaged from the frame by endwise movement and any one of them may be inserted or removed from the frame without disturbing either of the other sections. The section 9 is held in the frame beneath the

bead 7, the lip 12 at one end and the locking device 13 at the other end. This locking device is in the form of a tongue formed by cutting away some of the material of the frame, as best shown in Fig. 2, and it is provided with a stop 13' to engage the end 55 of the plate section 9 opposite the end which is engaged by the lip 12. The plate section 9 has a projection 14 at the end which is engaged by the locking device, and this projection extends upward and is engaged by a 60 lip 14' on the frame, the section 10 being cut away at 14'' to accommodate the lip 14'. The middle plate section 10 is held on the frame beneath the lip 15 at one end, the lips 16 and 17 engaging the top and bottom 65 edges respectively of the section at the opposite end of the section and the locking device 18 having a stop 18' to engage the end of the section between the lips 16 and 17.

The section 11 is held on the frame beneath the lip 19 which engages one end of the section, the lip 20 which engages the bottom edge of the section at the corner beneath the lip 19, the top lips 21, the locking device 22 having the stop 22' and the lip 23 70 75 engaging the bottom edge of the section at the corner below the locking device 22.

The upper corner of the lower section 9 is slightly cut away at 24 at the end which is first inserted in the frame, to accommodate 80 85 the lip 17. The middle section 10 is provided with projections on its lower edge to engage the top edge of the lower section 9. The upper corner of the middle section is slightly cut away at 26 at the end which is 90 first inserted in the frame to accommodate the lip 23. The lip 20 is spaced from the lip 16 and the lower corner of the upper section 11 is cut away at 27 at the end of the section which is first inserted in the frame to 95

accommodate the lip 20, and this section is provided with projections 28 on its lower edge to engage the top edge of the middle section 10. The top edge of the upper plate 11 is cut away at 19' at the end which is 100 first inserted in the frame to insure clearance from the lip 31. I prefer to provide the lower edges of the sections 10 and 11 with the contact projections 25 and 28 at or adjacent the ends of the sections because it 105 is found that this facilitates insertion and removal of the sections by reducing the edge contact of the sections. The middle section

is inserted in the frame by sliding it endwise from right to left over the locking device 18 and the upper and lower sections are inserted in the frame by sliding them endwise from left to right over the locking devices 13 and 22 respectively. The construction of the plate sections and the construction and arrangement of the retaining devices is such that the three plate sections are arranged in edge contact to insure proper line spacing of the type characters and yet any one of the sections may be inserted or removed without affecting either of the other sections.

15 The card 29 is removably engaged with the bead 6, the corner lip 30, the bottom lips 31 and the end stop 32. The card bears printed matter relating to the printing device and it may be an impression from one 20 of the plate sections, or a part thereof, or it may bear other information data. The card is insertable in and removable from the frame in a somewhat similar manner to the printing plate sections. The card is located 25 at the top of the frame above the upper plate section 11 and over a plurality of keepers 33 which receive one or more removable tabs 34.

The invention provides a frame and plate section construction which has been found 30 to be highly desirable in special classes of work, the plate sections can be easily inserted and removed from the frame separately without affecting each other, they are held in substantially fixed position in the frame in edge contact to insure proper line 35 spacing, and the retaining means are disposed on the frame in a manner which will permit the plate sections to be easily inserted and removed and which will hold them in 40 proper position on the frame and which do not weaken the frame for the purposes for which it is intended.

While I intend and prefer that the devices shall be made, as they have been made, as illustrated in the drawings as herein described, I reserve the right to make such changes in the form, construction and arrangement of parts as come within the scope of the following claims.

50 I claim:

1. A printing device of the character described comprising a frame, and three separate printing plate sections removably secured in place thereon one above the other 55 in edge contact one with the other, said frame having retaining means stamped therefrom to engage and hold the plate sec-

tions, the middle section being insertable in and removable from the frame at one end thereof and the upper and lower sections being insertable in and removable from the frame at the other end thereof.

2. A printing device of the character described comprising a frame, and three separate printing plate sections removably secured in place thereon one above the other and in edge contact one with the other, said frame having retaining means stamped therefrom to engage and hold the plate sections, and said means comprising a yieldable locking device for each plate section to engage an end thereof and lips to engage edges thereof, said locking devices being disposed alternately at the ends of the frame to engage one end of the middle section and the opposite ends of the upper and lower sections, whereby the middle section is insertable in and removable from the frame over its locking device at one end of the frame and the upper and lower sections are insertable in and removable from the frame over the locking devices at the other end of the frame, and the lips are disposed with relation to the sections to permit edge contact of the sections and the endwise insertion and removal of the sections without interfering one with another.

3. A printing device of the character described comprising a frame, and three separate printing plate sections removably secured in place thereon one above the other and in edge contact one with the other, said frame having retaining means stamped therefrom to engage and hold the plate sections, and said means comprising a locking device to engage one end of the middle plate section and locking devices to engage the opposite ends of the upper and lower plate sections, a lip to engage the end of each plate section opposite the end which is engaged by the locking device, a lip located above the locking device to engage the upper edge of the lower plate section, lips above and below the locking device to engage the end of the middle plate section, a lip below the locking device to engage the end of the upper plate section, a lip to engage the lower corner of the end of the upper plate section which is engaged by the end lip and the lower corner of this end of the upper plate section being cut away to accommodate the lip for the upper corner of the middle plate section.

HENRY E. HUBBARD.
